UNITED STATES PATENT OFFICE.

WALTER C. SWEENEY, OF TOPEKA, KANSAS.

POISON-INDICATOR.

1,157,338.

Specification of Letters Patent.

Patented Oct. 19, 1915.

Application filed November 28, 1914. Serial No. 874,484.

To all whom it may concern:

Be it known that I, WALTER C. SWEENEY, a citizen of the United States, residing at Topeka, in the county of Shawnee and State of Kansas, have invented certain new and useful Improvements in Poison-Indicators, of which the following is a specification, reference being had to the accompanying drawings.

10 This invention relates to new and useful improvements in safety devices and more particularly to an indicator adapted to be attached to the neck of a bottle, the main object of the present invention being the provision of a clamping device which can be quickly and readily applied to the neck of the bottle and which is adapted to be used for indicating that poison is contained within the bottle and is also used for retaining 15 the cork of the bottle in the neck thereof.

Another object of the present invention is the provision of an indicating device of the above character which will possess advantages in points of efficiency and durability is inexpensive to manufacture and, at 20 the same time, is simple in construction and operation.

With the above and other objects in view, the invention consists in the novel features 30 of construction, combination and arrangement of parts as will be hereinafter referred to and more particularly pointed out in the specification and claims.

In the accompanying drawing forming a 35 part of this application, Figure 1 is a front elevation of an indicator constructed in accordance with my invention, illustrating the same applied to the neck of a bottle. Fig. 2 is a side elevation taken directly opposite Fig. 1. Fig. 3 is a similar view illustrating the strap in an inoperative position. Fig. 4 is a vertical sectional view of the indicator as applied to the neck of the bottle. Fig. 5 is a detail perspective view illustrating the ends of the straps connected together. Fig. 6 is a detail perspective view of one of the retaining members. Fig. 7 is a transverse longitudinal sectional view of the connected ends of the strap; and Fig. 50 8 is a plan view of the blank.

In carrying out my invention, I provide a metal band generally indicated by the numeral 1, and extending outwardly therefrom, is an arm 2, said band and arm 2 being 55 preferably formed of thirty-eight gage

steel and is to be of sufficient resiliency so that they can be readily bent into different shapes. The band 1 is to be applied to the neck of the bottle and is so arranged that it can be fixed to necks of various sizes. In 60 order to carry this out, I provide one end of the band with a plurality of V-shaped notches, the material cut therefrom being adapted to form engaging points which coact with openings formed in the other end of the band, whereby to retain the band in various adjusted positions. In applying the same to the neck of a bottle, the end which is generally indicated by the numeral 3, is inserted through the sleeves or retaining 65 clips 4, upon the opposite end of the band, whereby to prevent lateral movement of the end 3.

The arm or extension 2 is provided with zigzag notches which are generally indicated by the numeral 5. After the band 1 has been applied to the neck of the bottle and in order to secure the cork in position, the arm 2 is bent to engage over the cork, as indicated in Fig. 2 and the notches or 70 recesses 5 engage with the T-shaped projections 6 which are formed in the end of the band 1, opposite the end 3. From this it will be apparent that the arm 2 after being bent over the cork, will be securely held in 75 position so that it cannot be opened by children, thus eliminating the danger of poison being taken by mistake. It will also be noted that the device forms a suitable indicating member which will indicate to the 80 person desiring to use the contents of the bottle that the same is poison. In addition to the above, the word poison is to be printed upon the main band 1, and also upon the arm 2, a number of skulls and 85 cross-bones will be indicated.

From the above it will be apparent that I have provided a simple and durable device of the character described which can be quickly and readily applied to the bottles 90 having various size necks and, at the same time, the device can be manufactured and placed upon the market at a comparatively 95 low cost.

While I have shown and described the 100 preferred form of my invention, it will be obvious that various changes in the details of construction and in the proportions may be restored to for successfully carrying my 105 invention into practice, without sacrificing 110

any of the novel features or departing from the scope of the invention, as defined by the appended claim.

Having thus fully described my invention, what I desire to claim and secure by Letters Patent, is:—

A retainer for bottle stoppers formed from a single blank of sheet metal and including a band portion adapted to embrace the neck of the bottle, one terminal of said band being provided with a plurality of longitudinally spaced openings, and the other terminal of the band being provided with longitudinally spaced spurs adapted to be projected through the openings, a plurality of laterally extending retaining members formed on the longitudinal edges of one terminal portion of the band, said re-

20 taining members being adapted to be bent to embrace the other terminal portion of the band, an arm extending at right angles to the band, said arm being provided with a plurality of slots and being adapted to be passed over the stopper, and T-shaped projections formed on the band at the intermediate portion thereof, said projections being adapted for insertion through the slots for holding the arm in engagement with the stopper.

25 In testimony whereof I hereunto affix my 30 signature in presence of two witnesses.

WALTER C. SWEENEY.
